UNITED STATES PATENT OFFICE

2,665,047

SHIPPING CONTAINER FOR HEAVY BULK MERCHANDISE

Jack R. Belsinger, Atlanta, Ga., assignor to Belsinger, Inc., Atlanta, Ga., a corporation of Georgia

Application November 8, 1950, Serial No. 194,677

1 Claim. (Cl. 229—14)

1

This invention relates to a shipping carton of paperboard material particularly adapted for heavy bulk merchandise such as nails, rivets, and like articles.

It has heretofore been the practice to ship standard quantities, such as one hundred pounds, of such heavy bulk articles in wooden kegs and like containers, largely for the reason that paperboard boxes have not been able to withstand the tests demanded prior to certification of such containers for general freight and express shipments, or such paperboard boxes have been of such complex and expensive construction that their use has been limited by economic factors incident to manufacture or loading thereof.

One of the features of the present invention is the provision of a paperboard box or carton having reinforcing members at the parts which have been found most subject to penetration from the exterior or interior during the shipment of such goods.

Another feature of the invention is the provision of a simple but adequately reinforced carton or box for such materials, which can be handled, loaded, shipped, opened, and discharged without major changes from existing methods employed with wooden kegs in present practice of packing, and with greater facility of opening and discharge than with such wooden kegs.

A further feature of the invention is the provision of a container for such materials, in which the several parts provide reinforced walls at all points of contact of the lading therewith.

With these and other features in view, as will appear in the course of the following description and claim, an illustrative form of practicing the invention is shown on the accompanying drawings, in which:

Fig. 1 is a perspective view of the assembled, loaded, and sealed container.

Fig. 2 is a perspective view showing upper and lower parts of the container in separated relative position, with the lower part thereof shown in condition for loading.

Fig. 3 is an upright sectional view, on a larger scale, through a side wall and through part of the bottom wall of such a container.

Fig. 4 is a view, on a smaller scale than that of the foregoing figures, showing a blank for forming an end cap.

Fig. 5 is a view on a scale smaller than that of Fig. 4, showing a blank for forming the side walls of a liner section.

Fig. 6 is a view on the scale of Fig. 5, showing a blank for forming the side walls of an outer section.

Fig. 7 is a view on the scale of Fig. 5, of a reinforcement pad.

In these drawings, the shipping carton or box is made of a paperboard material such as corrugated

2

board, fiber board, or the like. It is comprised of two outer sections and a liner section, the liner section being illustratively secured in the lower outer section during assembly, as shown in Fig. 2. The two outer sections are of identical horizontal cross section, being preferably symmetrical with respect to one another, so that when their free edges are brought into abutment, the adjacent outer surfaces are flush with one another.

To construct the carton or box, two blanks as shown in Fig. 6 are utilized. Each of these blanks has a series of four panels 10, 11, 12, 13, and an edge tab 14 illustrated as integral but separated by parallel fold lines 15. Such a blank is folded to form the four side walls for the outer section, with the edge tab 14 folded inside of the panel 10 (see Fig. 2) and stitched by the usual operation with staples 16.

Two end cap blanks are employed, as shown in Fig. 4. Each of these blanks has a central closing portion 18 formed integrally across fold lines 19, 20 with the flanges 21, 22. Gashes 24 aligned with the fold lines 19 provide corner flaps 25 connected with the adjacent flanges 21 across the extended portions of the fold lines 20. By construction, the opposed pairs of edges of the central closing portion 18, provided at the fold lines 19, 20, are respectively equal to the horizontal dimensions of the wall panels 10, 12 and 11, 13 of Fig. 6. The peripheral flanges 21, 22 of the blank in Fig. 4 are folded to positions at right angles to the central closing portion 18, with the corner flaps 25 turned to overlap the flanges 22, Fig. 2.

A reinforcing pad 28, Fig. 7, is provided for each of the outer sections. This pad has a surface of essentially the shape and area of the central closing portion 18 of the end cap blank, so that it has likewise the shape and area provided inside of the flanges 21, 22 thereof when folded at right angles; and it likewise has essentially the same size and shape as the external cross sectional shape of the side wall blank of Fig. 6 when folded and assembled into the form of a tube. Such a pad 28 is placed over the end of the side wall tube, and then the folded end cap piece is placed thereover, the parts are drawn tightly together, and secured by the staples 30. Thus, on the one hand, the pad 28 holds the central closing portion 18 of the end cap spaced from the adjacent edges of the side wall tube structure and, on the other hand, it tightly fits in this space so that it cannot later be dislocated as a result of internal or external blows upon the carton, and thereby reinforces against perforation and against distortion of the shape of the end cap and side wall structure. This provides a structure as shown by the upper section in Fig. 2. The end caps are positioned on each of the two

outer section tubes so that the overlaps of the edge tab 14 with the panel 10, in the respective outer sections, can be brought into direct abutment as shown in Fig. 2: that is, the two outer sections are symmetrical with respect to one another.

The blank for the inner liner section, shown in Fig. 5, has the side wall portions 35, 36, 31 and 38, and an edge tab 39 connected integrally across parallel fold lines 40. This blank is then likewise folded and its edge tab 39 brought inside for overlapping the free vertical edge of the side wall 35, and is stitched thereto by staples 41, Fig. 2. The horizontal dimensions of the respective side wall panels 35, 36, 37, 38 so correspond to the dimensions of the side wall panels 10, 11, 12, 13, that the outer sections have tight telescoping fits over the liner section.

The assembled liner section is then introduced into one of the outer sections, and forced downward therein until its lower edge abuts the reinforcing pad 28 thereof. It is then preferred to secure the liner tube in position in this lower outer section by staples 45, at least one such staple being located adjacent the mid-point of each free side wall edge of the lower outer section, as shown in Fig. 2.

This assembled lower structure, as shown in the lower part of Fig. 2, is then ready for loading with the material to be shipped. It will be noted that the upper opening is of the full internal size of the container, and defines the internal volume of this container, wherewith a tight filling to the level of this upper opening will produce a tight filling of the completed package. The lower structure and its contents can be shaken as an incident of loading, in the usual way, to obtain a tight filling with the predetermined weight of merchandise, to level condition. The upper outer section is then placed in the general position shown in Fig. 2, and is introduced over the liner section and slid telescopingly downward into place until the free edges of the outer sections come into abutment and the wall panels forming the outer surfaces of the side walls provide a series of planes across the abutment lines. Simultaneously with this abutment of the free edges of the outer sections, the inner surface of the pad 18 provided in the upper section comes into contact with the upper edge of the liner structure, Fig. 3.

The parts may now be held in such condition by applying a cemented tape 50 extending peripherally around the side walls and secured to each side wall panel of the upper and lower sections. It will be noted that such tape is strong in tension, and that it extends in plane across the abutment lines from one section to the other so that its tensile strength is effective to hold the outer members in the stated abutting position.

The abutting engagement of the free edges of the tube forming the liner section, with the inner surfaces of the reinforcing pads 28, further supports these pads against departure from their position, and prevents nails from gaining access to the free edge of the respective pad 28, whereby to wedge or deform these pads from their positioned shape and condition.

The structure, thus filled, assembled and sealed, has doubled walls throughout, with the several wall panels held in position by adjacent wall panels and cap portions; and with employment of the lower portions of the liner and the side walls of the bottom section for stiffening one another during filling, wherewith the upper

portion of the liner is held strongly to permit the placing of the upper section thereon. The upper and lower sections of the container have doubled top and bottom walls adjacent the upper and lower edges; and at least tripled walls are provided at the lower and upper parts of the sides; thus affording a great stiffness against deformation under the conditions of shipping and handling.

When it is desired to open and discharge the container, the tape 50 is slit by a knife, for example, along the lines of abutment, whereupon the upper section can be removed, therewith leaving the lower section as shown in Fig. 2, with the contents easily exposed for removal individually or in hand-fulls. Further, the smooth internal walls of the container permit a much more easy discharge, by inversion, than can be accomplished by inverting a wooden keg.

The container has a regular shape, requiring small space for shipment and storage, and readily adapts itself to position beneath a counter in a hardware store, and permits re-covering by the upper section when it is desirable to prevent the access of dust or moisture to such contents as iron nails.

While a sealing band 50 has been described in detail for holding the sections in closed position, it is to be understood that in place of the sealing band or in conjunction therewith any of the well-known metal bailing bands may be employed. Such a bailing band is indicated at 51 in Figure 1 of the drawings.

It is obvious that the invention may be employed in other ways than those illustrated within the scope of the appended claim.

I claim:

A shipping container of paper board material comprising a tubular inner member having connected side walls and upper and lower outer closure sections telescopingly fitting over the opposite end portions of said inner tubular member and being of such depth as to extend into substantially abutted relation, each outer section including an end cap having a central portion for closing the open end of the section and flanges extending from each side of said central portion and overlapping the side walls of said section and fixedly secured thereto, each outer section having an end pad contacting the inner face of said central portion and shaped and dimensioned so as to extend over the ends of the side walls of the section and into engagement with the flanges whereby the means for securing the flanges to the side walls of the section will secure said pad in place in said section as a unit therewith, and provide double end walls with the ends of the inner member in substantially abutted relation with the pads when the container is closed.
